BIT

Paul Manteros, Nashua, N. H.

Application August 3, 1940, Serial No. 351,029

3 Claims. (Cl. 144—233)

The general object of the invention is to provide a bit having attached blades; and which is adaptable to receive blades of a great variety of form, size, and order of dispositions on the bit, depending upon the character of the work to be done.

The invention can best be seen and understood by reference to the drawings in which—

Fig. 1 shows the complete bit in side elevation.

Fig. 2 is a plan.

Fig. 3 is the same as Fig. 1 but with the parts disassembled.

Fig. 4 is a side element of the bit fitted with long blades, as will later be referred to.

Fig. 5 is a side elevation of the bit fitted with short blades.

Fig. 6 is a side elevation of the body of the bit with spindle removed and fitted with a set of blades.

Fig. 7 is a side elevation of the body of the bit fitted with blades set differently than as shown in Fig. 6.

Fig. 8 is a plan of the bit as shown in Fig. 7.

Fig. 9 is a perspective of one of the blades of Fig. 5.

Fig. 10 shows in side elevation a modification of the invention with the parts disassembled.

Fig. 11 is a side elevation the same as in Fig. 10, with the parts assembled.

Fig. 12 is a view mainly in vertical cross section of the bit shown in Fig. 10; and

Fig. 13 is the same as Fig. 10 except that it shows a different type cutting blade.

1 represents the body of the bit. This body is generally disc-shaped and of appreciable diameter and thickness. Projecting from its under side, preferably integrally connected, is a shank 2 by which the bit is secured to any suitable motor unit (not shown) for purposes of rotation.

The top side of the body 1 is crossed diametrically by a deep blade receiving incision 3. It has, also, other blade receiving incisions 3' parallelly arranged and in staggered relation to each other, and preferably entering the body with inclination, as at any acute angle. Blades set into the incisions are held in place by set screws 4 which enter threaded sockets 5 in the body 1 and engage the embedded portion of each of the blades at substantially right angle to it.

Rising from the body 1 is a stepped spindle 6. At its lower end this spindle is provided with an annular flange 7 which is fixedly secured to the body 1 by screws 8 after centering by a pin 9 projecting downwardly from the centre of the flange

and entering a socket 10 at the centre of the body 1.

Above its attaching flange 7 the spindle presents a bottom step 11 generally tubular in form and presenting a plain cylindrical outer surface. Rising from the step 11 is a step 12 generally tubular in form with diameter less than the step 11, and presenting a threaded outer surface. At its top end the step 12 has a plain conical end 13 from which rises the third step 14 generally tubular in form of less diameter than the step 12 and with threaded outer surface. The spindle thus stepped is preferably made from a single solid piece of metal.

15 By means of cuts extending radially through the flange 7 of the spindle and rising vertically along the sides of its steps 11 and 12 blade receiving incisions 15 are formed thereon. These blade receiving incisions lie diametrically opposed to one another entering from opposite sides of the flange 7 and the spindle and are coincident with the blade receiving incision 3 in the body 1. Thus blades set into the incisions 15 of the flange 7 and spindle will lie along their lower edge portions within the incision 3 in the body 1, and accordingly will be held in by the set screws 4 which hold all blades entering this incision.

The blades thus set into the body of the bit and spindle are also held in place by pressure applied from above to the top ends of the blades, but this depends upon the length of the blades for blades of different lengths may be employed.

Shorter blades applied to the body and spindle rise above the step 11 and onto the step 12 (see Fig. 5), but not above the threads on this step. 35 These blades are held down from above by a tubular sleeve 16 threaded into the step 12. This sleeve when tightened exerts strong pressure on the top ends of the short blades thereby assisting in holding them in place. The top edge 17 of the sleeve 16 is made scalloped to facilitate its turning.

Longer blades applied to the body of the bit and spindle (see Fig. 4) rise above the step 12 and onto the step 14. These blades are held down by a sleeve 18 applied to the threaded surface of the step 14 and having a squared head 19 by which it may be turned.

Thus the bit is made adaptable for receiving 45 a great variety of blades both in size, form, and relative disposition on the bit, depending upon the work to be done.

When the bit is used without the spindle, as it may be used, blades a, a, or a', a' are placed 55 within the incision 3, or within the incisions 3'

within the body 1, as shown in Figs. 6 and 7. These blades are especially adapted for doing sinkage work, such as rosettes, panellings, groovings, or the like.

When the bit is used with the spindle applied to the body, as shown in Figs. 4 and 5, then blades b, or b' are applied to the bit, b representing the shorter blades and b' the longer blades. These blades are fixedly secured in place as previously explained.

The blades applied to the combined body and spindle are especially adaptable for lateral or edge cutting as in the making of mouldings and the like. During this cutting the work rests upon a table and is applied to the cutting blades in the usual manner. As the bit follows along the side or edge of the work for obtaining a cutting therein this edge along which the bit is working will, when the shorter blades are employed, bear against the sleeve 16 and, when the longer blades are employed, against the sleeve 18. These sleeves against which the work is bearing are rotating at a very high speed and are susceptible to excessive wear owing to continued bearing of the work against them. They are made, however, of a material much harder than that of the body of the bit or spindle so as to withstand the wear. In this connection it will be observed that the sleeves 16 and 18 perform a double function inasmuch as they act not only to assist in holding the blades in place but also present bearing surfaces along which the work may follow.

The blades themselves are made from flat stock which permits of convenience and economy in their making, and sharpening. They are made in a great variety of forms, the particular blades to be used, and their disposition on the bit, varying with the work to be done.

For certain types of work it is desirable that the work engage bearing surfaces above and below the cutting blade. Accordingly, in Figs. 10 to 13, inclusive, modification is shown in order that this end may be secured. Here the spindle is provided with a blade receiving incision and arranged upon the spindle are rings 21. The blade c lies between sets of these rings and is embedded in part within the incision in the spindle. The part of the blade thus embedded is provided at opposite ends with outstanding flanges 22 which lie in back of the adjacent rings. Rings and blade are then held bound together by the sleeve-like nut in the threaded portion of the spindle which, when tightened against the ring adjacent to it, acts to bind rings and blade together and hold the blade securely in place.

I claim:

1. A bit having a body attachable for rotation, a stepped spindle connected thereto and rising therefrom, said spindle comprising a lower step and an upper step, said upper step being of lesser

diameter than the lower step and having a threaded external surface, said body and spindle being provided with a blade receiving incision by which a contained blade will lie embedded in part within said body and in part within said spindle with extension onto the threaded portion of the upper step thereof, means for holding a blade thus embedded in place including a member borne by said body adapted and arranged to exert lateral pressure against that portion of the blade embedded within said body, and a member on the threaded step of said spindle adapted and arranged when tightened to have engagement with the top end portion of said blade.

5 2. A bit having a body attachable for rotation, a stepped spindle connected to said body, said spindle comprising a lower step and steps rising therefrom gradually lessening in diameter and each presenting a threaded external surface, said body and spindle being provided with a blade receiving incision by which a contained blade will lie embedded in part within said body and in part within said spindle with extension onto some threaded step of said spindle depending upon the length of the blade, means for holding a blade thus embedded in place including a member borne by said body adapted and arranged to exert lateral pressure against that portion of the blade embedded within said body, and members arranged on the respective threaded steps of said spindle each adapted and arranged when tightened to have selective bearing engagement with the top end portion of the blade extending onto its threads.

15 3. A bit having a body attachable for rotation and having therein a blade receiving incision within which a cutting blade will lie embedded, a stepped spindle comprising a flanged lower step and steps rising therefrom gradually lessening in diameter and each presenting a threaded external surface, said spindle being provided with a blade receiving incision cut through said flange with extension along said steps of the spindle and onto the uppermost threaded step thereof, means for securing said spindle to said body whereby the incision in the flange and spindle will lie coincident with the incision in said body in continuation thereof, means for holding a blade embedded within the incisions of said body and spindle including a member borne by said body adapted and arranged to exert lateral pressure against that portion of the blade embedded within said body, and members arranged on the respective threaded steps of said spindle each adapted and arranged when tightened to have selective bearing engagement with the top end portion of the blade extending onto its threads.

PAUL MANTEROS.
